UNITED STATES PATENT OFFICE.

ERNEST EUGENE CHAPMAN, OF DOYLESTOWN, ASSIGNOR OF ONE-HALF TO
FRED NOLLER, OF FOUNTAIN PRAIRIE, WISCONSIN.

GRAIN-SEPARATOR.

SPECIFICATION forming part of Letters Patent No. 432,370, dated July 15, 1890.

Application filed April 4, 1890. Serial No. 346,507. (No model.)

To all whom it may concern:

Be it known that I, ERNEST EUGENE CHAPMAN, a citizen of the United States, residing at Doylestown, in the county of Columbia and 5 State of Wisconsin, have invented a new and useful Grain-Separator, of which the following is a specification.

This invention relates to thrashing-machines and grain-separators; and it has for 10 its object to provide new and improved mechanism for conveying the straw, grain, and chaff from the thrashing-cylinder to the tail end of the machine, for separating the grain and straw from the chaff, and for returning 15 the grain to the front end of the machine, where it is eventually delivered.

In grain-separators as ordinarily constructed it has been customary to deliver the grain at the side of the machine near the tail end. 20 This has been objectionable, because this point of delivery has been very much exposed to the dust and chaff which have been blown out at the tail end of the machine. By my present improvement I aim to overcome this objection by returning the grain to and delivering it at the front end of the machine, where 25 it may be conveniently measured.

With these ends in view my invention consists in the improved construction, arrangement, and combination of parts, which will be 30 hereinafter fully described, and particularly pointed out in the claims.

In the accompanying drawings, in which I have shown only those parts of a grain-separator to which my invention distinctly relates, Figure 1 is a perspective view. Fig. 2 is a longitudinal vertical section. Fig. 3 is a vertical transverse section taken on the line 3 3 of Fig. 2. Fig. 4 is a vertical transverse 40 section taken on the line 4 4 in Fig. 2.

Like numerals of reference indicate like parts in all the figures of the drawings.

1 1 designate the sides of the frame, which are supported upon the sills 2 2.

45 It will be understood that in the drawings hereto annexed only a portion of the frame has been shown, for the purpose of showing more clearly the parts of the machine to which my invention especially relates.

The sides 1 1 are provided near their front 50 ends with bearings for a transverse shaft 3, in rear of which boxes 4 are mounted, forming bearings for a transverse shaft 5. The shafts 3 and 5, to either of which motion may be communicated, either from the cylinder- 55 shaft or from any other suitable part of the machine, are provided with pulleys designated, respectively, 6 and 7, the pulley 7 upon the shaft 5 being the larger of the two. The pulleys 6 and 7 are connected by a twisted 60 belt 8, whereby the shafts 5 and 3 are rotated in opposite directions, the shaft 3 at a greater rate of speed than the shaft 5, as will be readily understood, owing to the proportions of 65 the parts.

9 designates a longitudinal trough or casing, which is provided on its under side near its front end with boxes 10, journaled upon a crank 11 upon the shaft 5. The sides of the said trough or casing are extended in the 70 rear, forming arms or brackets 12, which are connected pivotally with the upper ends of spring-supports 13, secured near their rear ends to the sides of the frame. It will be seen that by this method of mounting the trough, 75 when the crank-shaft 5 is in operation, the front end of said trough will receive a vibratory movement, while its rear end will receive a peculiar jerky motion, caused by the spring-supports 13, upon which it rests, and which I 80 have found particularly desirable for effecting the purposes of my invention.

The upper edges of the side pieces of the trough 9 are provided with cross-pieces or braces 14, supporting the side pieces 15 of 85 the straw conveyer and separator. Said side pieces are each provided with a series of upwardly and rearwardly inclined steps 16, having vertical rear walls 17, and provided in their upper sides with inclined notches 18. 90 In these notches are secured the transverse slats 19, the rear edge of each of which is elevated slightly above the front edge of the one next in rear of it. These slats form a series of independent steps that serve to sift 95 or screen the grain and chaff from the straw, as will be presently more fully described.

The rear ends of the sides 15 of the straw-

conveyer are provided with upwardly-curved extensions 20, the upper edges of which are provided with inclined notches 21, in which transverse slats 22 are seated in like manner 5 as the slats 19 in the notches 18. The slats 22 are provided with upwardly and rearwardly inclined teeth or spurs 23.

The under sides of the rearward extensions 20 are provided with a bottom 24, composed 10 of a series of steps 25, having approximately horizontal or upwardly and rearwardly inclined upper sides and abrupt or approximately vertical front edges. This floor terminates a short distance in the rear of the 15 floor 26 of the trough 9. Said floor 26 is provided with a series of transverse ribs or ridges 27, inclined upwardly and rearwardly and having vertical rear edges. Said ribs serve to convey the grain and chaff in a rearward 20 direction during the operation of the machine.

28 designates a shoe, which is arranged below the trough 9 directly under the rear or discharge end of the latter. Said shoe has a curved or concaved bottom, and its sides are 25 cut away, as will be seen at 29, to accommodate the fan-case 30, which is mounted between the sides of the casing or frame of the machine. The discharge-opening of the said fan-case is in alignment with the open front 30 end of the shoe. The sides of the latter converge forwardly and terminate in a tubular chute 31, which extends to the front end of the casing of the machine, where it is provided with a box 32, journaled upon a crank 33 on the shaft 3. The bottom of the chute 31, as 35 well as a portion of the bottom of the shoe, is provided with an upwardly and forwardly inclined transverse ribs or ridges 34, having approximately vertical front edges 35. The 40 shoe is connected pivotally, by means of laterally-extending pins or trunnions 36, with spring-supports 37, which are secured to the sides of the frame of the machine.

The operation is as follows: The motion imparted to the straw-conveyer and its attachments and to the shoe and conveying-chute is substantially the same, with the exception that the motion of the latter is reversed and at a slightly-greater rate of speed. The supporting-springs 37 being located near the front end, will also somewhat increase the jerky or vibratory movement. The machine should be run at a high rate of speed—say five hundred revolutions per minute—and the straw, grain, 45 and chaff as they leave the cylinder are delivered onto the straw-conveyer, by which they are fed gradually in a rearward direction. The grain and chaff will be thoroughly separated from the straw and will drop between the slats 50 19 onto the bottom of the trough or grain-conveyer 9. When the end of each of the steps 16 of the straw-conveyer is reached, the straw will be dropped violently over the wall 17 of said step upon the front end of the next step, 55 and the perfect separation of the grain and chaff from the straw will thus be greatly fa-

cilitated. The straw continues its rearward course until it is deposited upon the toothed slats 22 of the upwardly-curved rearward extensions 20, where the separation is completed 70 and whence the straw is eventually delivered to the straw-carrier. The grain and chaff which are dropped into the trough 9 are fed rearwardly by the motion of said trough until they drop over the rear edge of the bottom of the 75 latter and into the shoe 28. In dropping into the latter they are exposed to the blast of the fan contained in the case 30, by which the chaff is blown out through the tail end of the machine. In like manner the chaff is separated 80 from the grain which drops into the shoe from the floor 24 of the curved extensions 20 of the straw-conveyer. By the motion of the shoe and its forwardly-extending discharge chute the grain is fed forwardly through the 85 latter, and is eventually discharged at the front end of the machine, where it may be conveniently measured.

Having thus described my invention, what I claim is—

1. The combination of the grain-conveying trough having upwardly and rearwardly inclined transverse bottom ridges and the sides of which are provided with rearwardly-extending arms, the grain-conveyer mounted 95 upon said trough and having a series of upwardly and rearwardly inclined steps, each provided with a series of upwardly and rearwardly inclined transverse slats, the upwardly and rearwardly curved extensions of said 100 grain-conveyer, the transverse toothed slats mounted in inclined notches in the upper edges of said extensions, the floor for the latter having transverse ribs, a transverse crank-shaft supporting the front end of the grain-trough, and the springs supporting the rearwardly-extending arms of the latter, substantially as set forth.

2. The combination of the grain-conveying trough, the straw-conveyer mounted upon the 110 same, the shoe mounted below the discharge end of said grain-conveying trough and having the forwardly-extending chute, the crank-shaft supporting the front ends of said chute and the grain-conveying trough, and the 115 springs connected pivotally with and supporting the rearwardly-extending arms of the latter and the shoe, substantially as set forth.

3. The combination of the grain-conveyer having upwardly and rearwardly inclined 120 transverse ridges, the straw-conveyer mounted thereon and having upwardly and rearwardly inclined steps, each of which is provided with transverse upwardly and rearwardly inclined slats, the upwardly and rearwardly inclined extension of the straw-conveyer having transverse toothed slats and provided with a curved bottom the front end of which terminates in rear of the rear end of the bottom of the grain-conveyer, the shoe 125 arranged below the discharge end of the grain-conveyer and having a tubular dis-

charge-chute extending to the front end of the machine, the fan-case extending transversely across and in front of the shoe, the crank-shafts supporting the front ends of the grain-conveyer and of the discharge-chute, and the springs connected pivotally with and supporting the shoe, and arms extending rearwardly from the grain-conveyer, substantially as set forth.

In testimony that I claim the foregoing as my own I have hereto affixed my signature in presence of two witnesses.

ERNEST EUGENE CHAPMAN.
